BRUSHMAKING MACHINE

Alfred L. Le Febvre, Windsor, Conn., assignor to
The Fuller Brush Company, Hartford, Conn.,
a corporation of Connecticut

Application January 14, 1948, Serial No. 2,195

12 Claims. (Cl. 300—2)

1

A mechanism embodying the present invention is particularly adapted for use as a part of a brush making machine of the type disclosed in the application of Alfred L. Le Febvre for Brush Making Machine, Serial No. 666,735, filed May 2, 1946, now Patent 2,572,498, October 23, 1951. Reference is made to the said application for various features of the machine not herein fully shown and described.

A machine of the type referred to includes a fiber magazine carrying a mass of transversely arranged fibers, and includes a twisting mechanism spaced from the magazine, being preferably forwardly spaced. Associated with the fiber magazine and with the twisting mechanism is a movable carrier which is reciprocated between a magazine station adjacent the magazine and a twisting station adjacent the twisting mechanism. As the carrier is moved to the magazine station a longitudinal wire is placed thereon, and at the magazine station a layer of transverse fibers is transferred from the magazine and placed on the carrier above the said wire. As the carrier is moved to the twisting station a second wire is placed thereon above the layer of fibers, and in the twisting station the two wires are engaged by gripping devices, one of which is rotatable. The rotation of the rotatable gripping device twists the wires so as to grip the layer of fibers between them and a brush of the twisted wire type is formed.

The present invention relates particularly to the fiber magazine of the machine and to the parts directly associated therewith. The magazine is essentially a rectangular container open at the top and at the bottom, and transversely arranged fibers are placed therein by the operator so that a sufficient supply is always maintained. Movable across the bottom of the magazine are two similar, but oppositely formed, slicing knives or bars, which are reciprocated in unison so as to move in one direction during one cycle and in the opposite direction during the next following cycle. The bottom faces of these bars terminate in points at their adjacent ends and the said bars have inclined faces extending upward from their pointed ends. At the beginning of each cycle one of the slicing bars is beneath the mass of fibers in the magazine and the other slicing bar is at one side. During the cycle the first said bar is withdrawn from beneath the fibers, which move downward so as to be supported by the movable fiber carrier, and at the same time the second said bar is moved through the fibers in the magazine so as to serve to slice off a layer of fibers, which

2

layer remains on the carrier. During each slicing movement the main mass of fibers, above the sliced off layer, is forced upward by the last said slicing bar.

It has been found that, in machines as heretofore constructed, the fibers immediately adjacent each end wall of the magazine frequently fail to move downward to the full extent permitted by the retreating slicing bar with the result that no fibers, or an insufficient quantity of fibers, are deposited on the corresponding end of the carrier. Thus the layer of fibers sliced off by the advancing slicing bar is deficient at the said end. In accordance with the present invention each end wall of the magazine is vertically movable in unison with the movements of the slicing bars, so that, as the mass of fibers tends to move downward to the extent permitted by the retreating bar, the corresponding end wall also moves downward. The downward movement of the end wall causes the downward movement of the immediately adjacent fibers, thus insuring a fully filled layer of fibers on the corresponding end portion of the carrier.

The present invention relates not only to the vertically movable magazine end walls, but also to various other parts associated therewith.

The drawings show in detail a preferred embodiment of the invention, but it will be understood that various changes may be made from the construction shown, and that the drawings are not to be construed as defining or limiting the scope of the invention, the claims forming a part of this specification being relied upon for that purpose.

Of the drawings:

Fig. 1 is a front view of the fiber magazine of a machine embodying the invention, together with various parts associated with the magazine.

Fig. 2 is a transverse vertical sectional view of the carrier taken along the line 2—2 of Fig. 1.

Fig. 3 is a transverse vertical sectional view taken along the line 3—3 of Fig. 1.

Fig. 4 is a longitudinal vertical sectional view taken along the line 4—4 of Fig. 3.

Fig. 5 is a horizontal sectional view taken along the line 5—5 of Fig. 1.

Fig. 6 is a transverse vertical sectional view taken along the line 6—6 of Fig. 1.

Fig. 7 is a transverse vertical sectional view taken along the line 7—7 of Fig. 1.

Fig. 8 is a transverse vertical sectional view taken along the line 8—8 of Fig. 1.

Referring to the drawings, 10 is a carrier which is reciprocated between a magazine sta-

tion wherein it is associated with a fiber magazine as shown in Figs. 1 and 2, and a twisting station wherein it is associated with a twisting mechanism which is not shown. Preferably, the magazine station is at the rear and the twisting station is at the front. As explained in detail in the said copending application, the carrier 10 is supported on a transversely reciprocable slide 12. In addition to being reciprocated horizontally with the slide 12, the carrier may also be reciprocated vertically to properly cooperate with the fiber magazine and with the twisting mechanism. When the carrier is at the rear it is in a relatively elevated position and when it is at the front it is in a lower position.

The carrier 10 has parallel longitudinal front and rear walls 14 and 16 adapted to support a layer of transversely positioned fibers F. Preferably the said walls are provided with teeth or serrations which serve to hold the fibers in their transverse positions. The end walls of the carrier are notched to receive a lower longitudinal wire W. The carrier has a bottom wall 18 provided with a hollow downward extending tubular extension 20. The extension 20 is positioned in and fits an opening in the top of a vertically movable slide 22. The slide 22 is guided for vertical movement with respect to a bracket 24 on the main slide 12. The slide 22 extends through an opening in the main slide 12 and a suitable means, not shown, is provided for vertically reciprocating the slide 22 and the carrier 10 as the main slide 12 is horizontally reciprocated. As the main slide 12 is moved rearward, the slide 22 and the carrier 10 are moved upward to the position shown in Figs. 1 and 3. As the main slide is moved rearward, the slide 22 and the carrier 10 are moved downward to a position, not shown, where the carrier is adjacent a twisting mechanism.

The slide 22 has a vertical hole 26 which communicates with the interior of the carrier extension 20. The lower end of the hole 26 is connected with a suitable exhaust means so as to maintain a partial vacuum within the carrier.

During each cycle the carrier is moved rearward and also upward to the magazine station, and a lower wire W is deposited thereon in the notches in the carrier end walls before it reaches the said station. Preferably, the wire is deposited automatically during rearward movement by means of a suitable wire feeding mechanism, as disclosed in the said copending application. At the magazine station transverse fibers F are distributed on the carrier in the manner to be described in detail. Immediately following the distribution of fibers on the carrier, the said carrier is moved downward and forward to a twisting station. During forward and downward movement the partial vacuum in the carrier maintains the fibers in place. An upper wire, not shown, is deposited on the carrier above the fibers and above the lower wire. Preferably, the upper wire is deposited automatically during forward movement by the aforesaid wire feeding mechanism. At the twisting station the two wires are engaged by a suitable twisting mechanism and are twisted to grip the fibers and form a brush.

The fiber magazine is carried by an elevated platform 28 which is supported on the base of the machine by brackets 30 and 32. The platform has a recess in the front thereof in which the magazine is located. As shown most clearly in Fig. 5, the magazine comprises a vertical sheet

metal member 34, the main longitudinal portion of which constitutes the rear wall of the magazine. The member is provided at its ends with forward extending vertical flanges 36, 36. At the inner sides of the respective flanges 36 are vertical supporting bars 38 and 40 which are connected at their upper ends to brackets 42, 42 mounted on the platform 28, screws 44 extending through the brackets and into the bars. Screws 46 extend through each flange 36 and into the corresponding bar. Thus the two bars 38 and 40 serve to support the member 34.

Extending forward from the lower portion of each of the bars 38 and 40 are two headed studs 48 and 50, as most clearly shown in Fig. 6. These studs carry a vertical plate 52 which constitutes the front wall of the lower portion of the magazine. The plate 52 has inverted keyhole slots for receiving the studs 48 and bottom notches for receiving the studs 50. These studs and notches permit ready removal of the plate. Preferably, the plate 52 is formed of transparent material so that the fibers in the lower portion of the magazine can be readily seen.

Preferably, the screws 46 extend through horizontal slots 54 in the flanges 36 as shown in Fig. 3. These slots permit the member 34 to be adjusted forward or rearward from the position shown so as to accommodate fibers F of shorter or longer length. When the member 36 is adjusted in one direction, the plate 52 is correspondingly adjusted in the opposite direction. This is effected by turning the studs 48 and 50 so that they project to lesser or greater extents from the bars 38 and 40. Alternatively, studs of shorter or longer lengths may be substituted.

The magazine is provided with two longitudinally spaced end walls which are vertically movable independently of each other. These vertically movable end walls may be variously supported and guided and one suitable construction for this purpose is shown in the drawings and will be described in detail.

Secured to the vertical bar 38 are two superposed brackets 56, 56 which extend toward the left. The brackets 56, 56 carry transverse pins 58, 58, each of which has two rollers 60, 60 thereon at opposite sides of the corresponding bracket. A vertical right end wall 62 is provided for the magazine, this end wall engaging the rollers 60, 60 and being vertically movable. Connected with the end wall 62 and spaced toward the right therefrom are two pairs of guide bars 64, 64, the bars of each pair being at opposite sides of the corresponding bracket. These guide bars are so positioned that their left faces can engage the rollers 60, 60. Thus the rollers serve to guide the end wall for vertical movement. The spaces between the wall 62 and the guide bars 64, 64 are slightly greater than the diameter of the rollers.

A vertical left end wall 66 is provided for the magazine, this being also vertically movable. The end wall 66 may be connected with the vertical bar 40 in the same manner that the end wall 62 is connected with the vertical bar 38. Preferably, however, the left end wall 66 is adjustable longitudinally of the magazine to change the effective length thereof. When the end wall 66 is so adjustable it is connected with a vertical bar 68 which is horizontally adjustable with respect to the bar 40. A horizontal rod 69 extends through an aperture in the bar 40, being held in position by a set screw 70. The bar 68 is

secured to the right end of the said rod 69 and is supported in part thereby. Extending along the top of the magazine are horizontal rails 71, 71 having a slot between them. The upper portion of the bar 68 is connected with a bracket 72, and this bracket is secured to the rails 71, 71 by screws 73. When the screws 70 and 73 are loosened the rod 69 and the bracket 72 can be adjusted longitudinally of the machine to change the position of the bar 68. The vertically movable end wall 66 is connected with the bar 68 in the same manner that the end wall 62 is connected with the bar 38.

It will be seen that the left end wall 66 is not only vertically movable but is also adjustable longitudinally of the magazine to change the effective length of the magazine. Carriers 10 of different lengths may be provided for brushes of different lengths. The right end wall 62 of the magazine is in vertical register with the right end of the carrier, and the left end wall 66 of the magazine is adjusted so that it is in vertical register with the left end of the carrier. Preferably each of the vertically movable end walls 62 and 66 is provided at the bottom with a roller 74 for a purpose to be hereinafter set forth.

Vertical partitions 78, 78 depend from the rails 71, 71, two such partitions being shown. These partitions are carried by brackets 80, 80 which are adjustable along the rails 71, 71, being held in place by bolts 82, 82. When there are two partitions, they are so located that the longitudinal distance between the end walls 62 and 66 is divided into three equal portions.

Vertically movable in the spaces between the partitions and between the partitions and the end walls are pressure heads 84, 84 adapted to rest upon the fibers. Heads are chosen which are of the proper length to fit the said spaces. Each pressure head 84 is detachably connected with a vertical rod 86 guided for vertical movement in a bracket 88. Each bracket 88 is adjustable longitudinally of the machine in slots 90, 90 formed in plates 92, 92 carried by the platform 28, the bracket being held in adjusted position by bolts 94, 94. The brackets 88, 88 are longitudinally adjusted in accordance with the adjustment of the partitions 78, 78. Preferably, each head 84 has rearward and forward extending screws 96 and 98, the screws 96 being adapted to engage the rear wall 34 and the screws 98 being adapted to engage the front plate 52. When the front and rear walls of the magazine are adjusted for fibers of different lengths the screws 96 and 98 are correspondingly adjusted. Each head 84 has a finger piece 100 by which it can be readily lifted.

Fibers F are transferred from the bottom of the magazine to the carrier in a manner to be described, and the mass of fibers in the magazine is replenished by the operator. Bunches of fibers are placed in the spaces between the partitions and between the partitions and the end walls. When the fibers in any one of the spaces are depleted, the operator lifts the corresponding pressure head 84 by means of the finger piece 100 and inserts a bunch of fibers. Then the pressure head is released to press against the newly inserted fibers.

For removing fibers from the magazine and distributing them on the carrier, two similar but oppositely positioned slicing knives or bars 102 and 104 are provided. The bottom faces of these bars terminate at points at their adjacent ends

and the bars have inclined faces extending upward from their said pointed ends. The bars are connected together for movement in unison and they move in one direction during one cycle and in the opposite direction during the next following cycle. The paths of movement of the bars are such that they travel within the magazine with their bottom faces closely adjacent the top of the carrier 10 when the carrier is in its rearward and upward position as shown in the drawings.

The two slicing bars 102 and 104 are carried by a slide 106 which is horizontally reciprocable in a guide rail 108 supported on the platform 28. The slide 106 has two pairs of forward projections 109, 110, the bar 102 being secured to the projections at the right and the bar 104 being secured to the projections at the left.

The slide 106 carries a rack 114 which meshes with a gear 112 mounted on a transverse shaft 114. Located at the rear of the machine is a longitudinally movable rack 116 which meshes with a gear 118 on the said shaft 114. Connected with the rack 116 is a bracket 120 which is connected to a longitudinally movable rod 122. The rod 122 is connected with a piston, not shown, which is movable in a cylinder 124 shown in Fig. 4. A suitable valve mechanism is provided which admits fluid to the cylinder 124 to move the piston therein toward the right or toward the left, thus correspondingly moving the rod 122 and the rack 116. When the piston and the rod are moved toward the right, as indicated by the arrow in Fig. 4, the gears 118 and 112 are rotated in the clockwise direction, thus moving the rack 114 and the slicing bars 102 and 104 toward the right, as indicated by the arrows in Figs. 1 and 5. When the piston and the rod 122 are moved toward the left, the described motions are reversed. The valve mechanism is so controlled automatically that during one cycle the bars are moved toward the right, and so that during the next following cycle the bars are moved toward the left. It will be understood that during each movement of the bars the carrier 10 is in its rearward and upward position as shown in the drawings.

When the carrier 10 first reaches the position shown in Fig. 1, the bars 102 and 104 are either at their extreme left positions or at their extreme right positions. As soon as the carrier reaches the said position the valve mechanism is operated to start the movement of the bars toward the right or toward the left as the case may be. The drawings show the bars in an intermediate position and moving toward the right.

Secured to the tops and bottoms of the projections 109 and 110 on the slide 106 are longitudinal angle bars 126 and 128. These angle bars support a longitudinal vertical plate 130 which is in register with the rear wall 34 of the magazine. The plate 130 is apertured to receive and fit around the projections 109 and 110. The upper edge of the plate is immediately adjacent the bottom edge of the wall 34, and the bottom of the plate is below the level of the top of the carrier. By means not shown the angle bars 126 and 128 can be moved with respect to the projections 109 so that the plate 130 can be adjusted in accordance with adjustments of the rear wall 34. The plate 130 constitutes the lower portion of the rear wall of the magazine, and is in effect a downward extension of the wall 34. The said plate prevents any rearward movement of the fibers which are below the bottom of the wall 34.

The plate 130 is necessarily movable in order to

permit the projections 110 to move into the bottom portion of the magazine below the wall 34. Means is provided for causing vertical movements of the end walls 62 and 66 in synchronism with the horizontal movements of the slicing bars. While the invention is not necessarily so limited, the slicing bars preferably directly serve in cooperation with the rollers 74, 74 at the bottoms of the end walls to cause the said end wall movements. The tops of the bars engage the said rollers, the result being that each end wall moves downward by gravity as one bar retreats and are forced upward as the other bar advances.

When the bar 102 was in its extreme left position it was beneath all of the fibers F in the magazine and served to support them. The bar was also in engagement with the rollers 74, 74 at the bottoms of the vertically movable end walls 62 and 66, the said end walls being thus held in relatively elevated positions. Movement 10 of the bar 102 toward the right to the position shown has permitted the end wall 66 to move downward by gravity to its lowermost position, and has permitted the fibers at the left side of the magazine to move downward under the influence of the pressure heads 84, 84. At the extreme left where the bar 102 has uncovered a portion of the carrier, the fibers have moved downward onto the carrier between the teeth thereon. The movable rear plate 130 prevents rearward movement of the fibers which have moved downward. Continued movement of the bar 102 toward the right permits the fibers to engage the carrier through the entire length thereof, thus establishing a layer of fibers on the carrier. As the bar 102 approaches its extreme right position, the right end wall 62 moves downward by gravity with the fibers to its lowermost position.

As the bar 102 retreats toward the right, the bar 104 advances in the same direction and it is forced through the fibers in the magazine. The bar 104 lifts all of the fibers except those which are below the lower face of the bar, the last said fibers remaining in a layer on the carrier. Advancing movement of the bar 104 also serves by engagement with the rollers 74, 74 to lift the two end walls 66 and 62 to their uppermost positions. A layer of fibers has been distributed on the carrier 10 and the carrier then moves downward and forward as already described to the twisting station where the wires on the carrier are twisted to grip the fibers and form a brush. Then the carrier is moved rearward and upward so that it is again in the position shown in the drawings. Then the operations heretofore described are repeated except that during the next following cycle the bars move from right to left instead of from left to right.

It will be understood that the end walls 62 and 66 are guided for vertical movement by the rollers 60, 60. Ordinarily the rollers are pressed in the outward directions by the fibers in the magazine and are thus held in engagement with the rollers. During normal operation the guide bars 64, 64 may not engage the rollers, but they nevertheless serve to prevent any substantial inward movements of the end walls.

It will be seen that the two slicing bars are moved in successive cycles first in one direction and then in the opposite direction. As they so move the two magazine end walls, during each cycle, are caused to move successively downward as one slicing bar retreats and are caused

5 to move successively upward as the other slicing bar advances.

Each of the vertical end walls 62 and 66 is provided with a notch extending upward from its bottom edge as clearly shown in Fig. 7. The notches are so located with respect to the path of movement of the slicing bars that the upper portions of the bars enter the said notches. Thus, the bottom edge of each magazine end wall is always below the upper face of that portion of the slicing bar which is within the notch in the end wall. This is important as it prevents any fiber from being moved longitudinally by the slicing bars underneath the end walls. The before-mentioned rollers 74 are adjacent the said notches.

When each vertically movable magazine end wall reaches its lowermost position, as shown at the left in Fig. 1, it engages with the carrier 14. This prevents any fibers from escaping longitudinally between the bottom of the end wall and the carrier.

In prior machines the end walls of the magazine have not been vertically movable. With a stationary end wall there is a tendency for some or all of the fibers near the bottom of the end wall to be frictionally held by the said wall so that they do not move freely downward onto the carrier. The result has been that the layer of fibers on the carrier did not extend throughout the entire length thereof, or was at least deficient in its extreme end portions. With the present construction the end walls move vertically with the fibers and as the fibers near the ends of the magazine move downward the end walls also move downward, thus insuring the complete filling of the layer at the ends thereof. Referring particularly to Fig. 1 of the drawing, it will be seen that the end wall 66 has moved downward with the fibers which are adjacent the said end wall, the said fibers being thus fully engaged with the corresponding end portion of the carrier.

In accordance with the invention, the end walls are movable vertically as described. In addition, provision has been made for adjustments of the magazine to accommodate fibers of different lengths and to accommodate carriers of different lengths.

The invention claimed is:

1. The combination in a brush making machine, of a magazine adapted for containing a mass of transverse horizontal fibers and having an open bottom, the said magazine including longitudinally spaced end walls which are vertically movable independently of each other, a longitudinally extending horizontal carrier for longitudinal horizontal wires and transverse horizontal fibers which carrier is movable in a direction perpendicular to its length to and from a fiber receiving position in which it serves to close the bottom of the magazine, two similar oppositely disposed longitudinally aligned horizontal slicing bars which are longitudinally spaced from each other and which at their inner ends terminate in points in the plane of their bottom faces with upward inclined faces extending oppositely from the said points, means for moving the said slicing bars horizontally in unison through the magazine alternately in opposite directions during successive cycles, the path of movement of the said slicing bars being such that the said points and bottom faces thereof move in close proximity to the top of the carrier in its fiber receiving position so that the retreating bar during each cycle permits fibers in the magazine to move downward

onto the carrier and so that the advancing bar during each cycle lifts the major portion of the fibers and slices off a bottom layer of fibers which remains on the carrier, and means for causing the two magazine end walls during each cycle to move successively downward as one slicing bar retreats through the magazine and permits the fibers to move downward and for causing the two magazine end walls during each cycle to move successively upward as the other slicing bar advances through the magazine and lifts the fibers.

2. A brush making machine as set forth in claim 1, wherein each movable magazine end wall upon moving downward engages with the carrier to prevent fibers from escaping longitudinally between the bottom of the end wall and the carrier.

3. A brush making machine as set forth in claim 1, wherein the means for causing the magazine end walls to move downward and upward includes two elements on the respective end walls directly engageable by both of the slicing bars.

4. The combination in a brush making machine, of a magazine adapted for containing a mass of transverse horizontal fibers and having an open bottom, the said magazine including longitudinally spaced end walls which are vertically movable independently of each other and which have notches extending upward from their bottom edges, a longitudinally extending horizontal carrier for longitudinal horizontal wires and transverse horizontal fibers which carrier is movable in a direction perpendicular to its length to and from a fiber receiving position in which it serves to close the bottom of the magazine, two similar oppositely disposed longitudinally aligned horizontal slicing bars which are longitudinally spaced from each other and which at their inner ends terminate in points in the plane of their bottom faces with upward inclined faces extending oppositely from the said points, means for moving the said slicing bars horizontally in unison through the magazine alternately in opposite directions during successive cycles, the path of movement of the said slicing bars being such that the upper portions of the bars enter the notches in the end walls and the path of movement of the said slicing bars being also such that the said points and bottom faces thereof move in close proximity to the top of the carrier in its fiber receiving position so that the retreating bar during each cycle permits fibers in the magazine to move downward onto the carrier and so that the advancing bar during each cycle lifts the major portion of the fibers and slices off a bottom layer of fibers which remains on the carrier, and means for causing the two magazine end walls during each cycle to move successively downward as one slicing bar retreats through the magazine and for causing the two magazine end walls during each cycle to move successively upward as the other slicing bar advances through the magazine, the said means for moving the end walls always maintaining the bottom edge of each end wall below the upper face of that portion of the slicing bar which is within the notch in the end wall.

5. A brush making machine as set forth in claim 4, wherein the means for causing the end walls to move downward and upward includes rollers on the end walls adjacent the said notches and engageable with the slicing bars.

6. A brush making machine as set forth in claim 1, comprising two stationary upright supporting bars adjacent the ends of the magazine,

and means on the said bars for guiding the respective end walls for vertical movement.

7. A brush making machine as set forth in claim 1, wherein superposed stationary rollers are provided adjacent each end wall for guiding the vertical movements thereof.

8. A brush making machine as set forth in claim 1, wherein superposed stationary rollers are provided adjacent each end wall for guiding the vertical movements thereof, and wherein guide bars are connected with the respective end walls and positioned for engagement with the opposite sides of the rollers.

9. A brush making machine as set forth in claim 1, comprising two upright supporting bars adjacent the ends of the magazine, two similar superposed brackets projecting inward from each upright bar, two rollers positioned at opposite sides of each bracket and engaging the corresponding end wall to guide it for vertical movement, and vertical guide bars positioned between each supporting bar and the corresponding end wall and connected with the latter, the guide bars being engageable with the rollers to prevent any substantial movement of the end wall away from the supporting bar.

10. The combination in a brush making machine, of a magazine adapted for containing a mass of transverse horizontal fibers and having an open bottom, the said magazine including longitudinally spaced end walls which are vertically movable independently of each other, means for longitudinally adjusting one of the vertically movable end walls to change the effective length of the magazine, a longitudinally extending horizontal carrier for longitudinal horizontal wires and transverse horizontal fibers which carrier is movable in a direction perpendicular to its length to and from a fiber receiving position in which it serves to close the bottom of the magazine, two similar oppositely disposed longitudinally aligned horizontal slicing bars which are longitudinally spaced from each other and which at their inner ends terminate in points in the plane of their bottom faces with upward inclined faces extending oppositely from the said points, means for moving the said slicing bars horizontally in unison through the magazine alternately in opposite directions during successive cycles, the path of movement of the said slicing bars being such that the said points and bottom faces thereof move in close proximity to the top of the carrier in its fiber receiving position so that the retreating bar during each cycle permits fibers in the magazine to move downward onto the carrier and so that the advancing bar during each cycle lifts the major portion of the fibers and slices off a bottom layer of fibers which remains on the carrier, and means for causing the two magazine end walls during each cycle to move successively downward as one slicing bar retreats through the magazine and permits the fibers to move downward and for causing the two magazine end walls to move successively upward as the other slicing bar advances through the magazine and lifts the fibers.

11. A brush making machine as set forth in claim 10, wherein the means for causing the magazine end walls to move downward and upward includes two elements on the respective end walls directly engageable by both of the slicing bars.

12. A brush making machine as set forth in claim 10, comprising two stationary upright supporting bars adjacent the ends of the magazine,

11

means on the said bars for guiding the respective end walls for vertical movement, and means for adjusting one of the supporting bars longitudinally of the magazine to correspondingly adjust the end wall guided thereon.

ALFRED L. LE FEBVRE.
